UNITED STATES PATENT OFFICE.

GEORGE M. EUSON, OF CHICAGO, ILLINOIS.

ARTICLE-CARRIER.

1,140,585.

Specification of Letters Patent. Patented May 25, 1915.

Application filed May 18, 1914. Serial No. 839,313.

To all whom it may concern:

Be it known that I, GEORGE M. EUSON, a citizen of the United States, residing at Chicago, in the county of Cook and State of Illinois, have invented certain new and useful Improvements in Article-Carriers, of which the following is a specification.

This invention relates to devices for carrying revolver holsters, its object being to provide a novel and improved shoulder suspension for the holster which enables the latter to be carried at any convenient position on the person.

This object is attained by means of a novel combination and arrangement of parts to be hereinafter described and claimed, reference being had to the accompanying drawing, in which an elevation of the device is shown.

In carrying out the present invention, there is provided a looped strap 5, each end of which carries a ring 6, and is also provided with a suitable adjusting buckle 7 to lengthen or shorten said end. The rings 6 carry short tabs 8 which are connected intermediate their ends by a spreader band 9, and the ends of said tabs carry fasteners 10 of any suitable design for connection to a revolver holster 11.

The strap 5 is designed to be hung over either shoulder or the neck of the person,

and it is adjustable to bring the holster 11 in any desired position. By shifting the strap around, the holster may be positioned in front of the body, to the rear, or at either side thereof. A universal adjustment is therefore provided, and the holster can be readily positioned as desired. The rings 6 provide a loose connection for the tabs 8 and allow the same to adjust themselves to the various positions of the strap so that the holster may hang properly. The device enables a revolver to be carried without feeling the weight thereof, it does not pull on the garment, and it readily adapts itself to the shape of the body no matter in what position it is carried.

I claim:

An article carrier comprising a looped strap spaced at its ends and having rings 50 thereat, tabs carried by said rings, fasteners on the tabs for the article to be carried, and a spreader band fastened to the tabs intermediate the ends thereof for connecting the same in spaced relation. 55

In testimony whereof I affix my signature in presence of two witnesses.

GEORGE M. EUSON.
